(57) **CLAIM**

The ornamental design for grip panels set for a gun as shown and described.

DESCRIPTION

FIG. 1 is a top perspective lateral view of the right grip panel of the grip panels set for a gun, showing the new ornamental design;

FIG. 2 is a top perspective medial view of the right grip panel of the grip panels set for a gun of FIG. 1;

FIG. 3 is a lateral view of the right grip panel of the grip panels set for a gun of FIG. 1;

FIG. 4 is a medial view of the right grip panel of the grip panels set for a gun of FIG. 1;

FIG. 5 is a top view of the right grip panel of the grip panels set for a gun of FIG. 1;

FIG. 6 is a back view of the right grip panel of the grip panels set for a gun of FIG. 1;

FIG. 7 is a front view of the right grip panel of the grip panels set for a gun of FIG. 1;

FIG. 8 is a top perspective lateral view of the left grip panel of the grip panels set for a gun, showing the new ornamental design;

FIG. 9 is a top perspective medial view of the left grip panel of the grip panels set for a gun of FIG. 8;

FIG. 10 is a lateral view of the left grip panel of the grip panels set for a gun of FIG. 8;

FIG. 11 is a medial view of the left grip panel of the grip panels set for a gun of FIG. 8;

FIG. 12 is a top view of the left grip panel of the grip panels set for a gun of FIG. 8;

FIG. 13 is a back view of the left grip panel of the grip panels set for a gun of FIG. 8; and

FIG. 14 is a front view of the left grip panel of the grip panels set for a gun of FIG. 8.
